UNITED STATES PATENT OFFICE.

JOHN M. MYERS, OF SCOTTSVILLE, KENTUCKY.

WELL-DRILLING MACHINE.

Application filed August 19, 1924. Serial No. 732,950.

To all whom it may concern:

Be it known that I, JOHN M. MYERS, a citizen of the United States, resident of Scottsville, in the county of Allen and State of Kentucky, have made a certain new and useful Invention in Well-Drilling Machines; and I declare the following to be a full, clear, and exact description of the same, such as will enable others skilled in the art 10 to which it appertains to make and use the invention, reference being had to the accompanying drawings, and to letters or figures of reference marked thereon, which form a part of this specification.

15 The invention has relation to well drilling machines, having for an object to provide an improved machine of simple and durable nature.

20 The invention consists in the novel construction and combination of parts, as hereinafter set forth.

In the accompanying drawings illustrating the invention, Figure 1 is a side view of the invention with parts broken away; 25 Figure 2 is a plan view of the invention; Figure 3 is a section on the line 3—3, Figure 2, and Figure 4 is a front view of the invention.

30 In these drawings the numeral 1 designates a wheeled support including front and rear bolsters 2 and 3, whereon is mounted the well drill frame consisting of a rectangular base 4, rear standards 5 having an upper cross bar connection 6, and inclined brace bars 7, a central rear post 8, being hinged to the upper cross bar at 9, and having a removable bolt connection 10 with the lower cross bar of the framing and at its 35 upper end carrying upper and lower pulleys 11 and 12.

40 The power shaft of the machine is indicated at 13, and is provided with a belt wheel 14, loosely mounted thereon and having an inner circular track 15, with which 45 a friction disk 16 upon a shaft 17 has driving engagement.

45 A horizontal drum 18 is loosely mounted on the power shaft 13, and is provided at one side with a large spur gear 19 fast thereto and forming an end flange thereof, and at the other side with a brake wheel 20 forming an end flange thereof, a hand lever 21 being adapted to tighten and to loosen the brake band 22 upon said brake 50 wheel, to thereby hold the drum 18 stationary, should occasion arise. The friction 55

drive aforesaid rotates the drum 18 to wind up the drill rope following descent of the drill through force of gravity, the rotation of said drum being accomplished by pinion 60 23 fast upon shaft 17, said pinion being slideable and being adjustable through hand lever 24 into mesh with said gear 19, and out of mesh therewith and into clutch with a drum 25, loosely mounted upon the shaft 65 17 and having at one side a clutch member 26, the complementary clutch member whereof is carried by said pinion.

A shaft 27 is mounted intermediate the height of the standards 5 above and in rear of drum 18 and is provided with a guide pulley 28, loosely mounted thereon, said shaft having fast thereto forwardly and upwardly projecting converging arms 29, carrying at the free end thereof a guide pulley 30 overlying the drum rope drum 18, said arms and the pulley carried thereby being rocked or vibrated up and down by crank 31 fast upon the power shaft 13 and having a roller 32 working in cam track 33 70 of rocker arm 34, the upper end of which is fast to the aforesaid shaft 27, said rocker arm projecting forwardly and downwardly from its shaft 27 at about right angles to 75 said arms 29.

In the working of the connecting rod 34, a helical spring 35 one end of which is fast to the framing and the other end of which is fast to shaft 27, is tightened or wound as the rocker pulley 30 is moved upward to let 80 out slack in the drill rope or cable 37 wound upon the drum 18 and passing first around said guide pulley 28, thence in the opposite direction around said rocker pulley, and thence in the opposite direction upwardly 85 over the pulley 12 at the top of the post 8, said rope then passing downwardly and carrying at its lower end the drill (not shown). As the rocker pulley is moved downwardly the helical spring in its 90 unwinding will assist in the raising of the drill.

The rope or cable 36 is wound upon the drum 25 and passes upwardly therefrom 100 over the pulley 11 at the upper end of the post 8, and at its lower end carries the casting or bailer (not shown) the latter being let down into the well as it is drilled by force of gravity and the rotation of said 105 drum, following which the hand lever 24 is operated to make the connection between pinion 23 and the drum, winding up the 110

cable 36. A hand lever 38 operates slideable clutch member 39 upon the power shaft 13 into and out of clutch engagement with the complementary member upon the hub of the power or belt wheel 14.

10 The auxiliary shaft 17 is pivoted at one end thereof at 40 and is movable pivotally through operation of a hand lever 41 to disengage the friction wheel 16 from the inner circular track of the belt wheel.

15 42 designates a small drum mounted rearwardly of the framing and having an operating shaft 43 provided with worm gearing connection with said drum, the latter carrying a cable which is designed to raise and lower the derrick or post 8.

20 Owing to the position of the shaft 27 above the drill rope drum 18 and the arms 29 projecting forwardly and upwardly from said shaft and carrying the guide pulley 30 overlying said drum and the guide pulley 28 upon said shaft, and the rocker arm 34 projecting forwardly and downwardly from said shaft at about right angles to said arms 29, the weight of the arms 29 and of the rocker arm 34 will, owing to the drill rope bend passing around pulleys 28 and 30, hold the drill rope taut in the return or upward movement of the drill.

25 30 Owing to the friction wheel 16 on shaft 17 being driven by contact with the inner circumferential surface of the belt wheel 14

it is possible to bring the two drums 18 and 25 more nearly together, so that there may be a gearing connection 19, 23 therebetween, 35 and the entire machine is rendered more compact, leaving room on the same supporting frame 7 for the engine driving the machine.

I claim:

40 In a well drilling machine, a power shaft having a belt wheel provided with an inner circumferential track, an auxiliary shaft provided with a friction wheel bearing against said track, a drill rope drum loose upon said power shaft and carrying a spur gear wheel, a casing rope drum loose upon said auxiliary shaft, a pinion fast upon said auxiliary shaft and having a clutch connection with said casing rope drum and being 50 slideable to release said clutch and mesh with said spur gear wheel, said auxiliary shaft being pivoted at one end and movable to disengage said friction wheel from said track, and a rock shaft carrying a drill rope 55 guide pulley and fast upwardly and forwardly projecting arms provided at their free ends with a drill rope guide pulley overlying said drill rope drum and a fast downwardly and forwardly projecting 60 rocker arm, said power shaft having a crank engaging said rocker arm.

In testimony whereof I affix my signature.

JOHN M. MYERS.
